UNITED STATES PATENT OFFICE.

ASMUS D. GARDEMAYER, OF SAN FRANCISCO, CALIFORNIA.

SASH-LOCK.

1,071,516.

Specification of Letters Patent. Patented Aug. 26, 1913.

Application filed June 28, 1912. Serial No. 706,529.

To all whom it may concern:

Be it known that I, ASMUS D. GARDEMAYER, a citizen of Germany, residing at San Francisco, in the county of San Francisco and State of California, have invented new and useful Improvements in Sash-Locks, of which the following is a specification.

This invention relates to sash locks and the object of the invention is to provide a simple and efficient device of this character by which both sashes may be locked in any adjusted position and prevented from rattling.

Further objects of this invention will appear as the following specific description is read in connection with the accompanying drawing, which forms a part of this application, and in which,—

Figure 1 is a front elevation showing the device applied. Fig. 2 is a section through the sash showing the device in top plan view. Fig. 3 is a similar view with the top plate removed. Fig. 4 is a sectional view on the line 4—4 of Fig. 2.

Referring more particularly to the drawing, 1 and 2 represent the top and bottom sashes, respectively, of an ordinary window. Secured to the bottom sash is a locking device which may be arranged adjacent either vertical rail of the upper sash. The device comprises a bottom plate 3 having a central longitudinal channel 4 formed therein, a portion of which is screw threaded, as shown at 5. The upper plate 6 is provided with a similar channel 2 having a screw threaded portion 8 to correspond with the threaded portion 5 and adapted to receive the operating screw 9 provided with a thumb button 10 at one end and with a head 11 at its opposite end. The channels 4 and 7 are enlarged adjacent the outer end of the plates 3 and 6 so as to receive a channeled head 12 formed on the pressure plate 13. The head

12 is adapted to be engaged by the head 11 on the screw 9 so that the pressure plate may be moved. In order to guide the pressure plate, the same is provided with a pair of parallel pins 14 arranged upon opposite sides of the head 12 and adapted to travel in the channels 15 formed in the plates 3 and 6. The lower plate 3 is provided with a downwardly extending flange 16 which is adapted to relieve the pressure on the attaching screws 17, which in this instance also join the plates together. By threading the screw into the plates 3 and 6, the pressure plate will be moved away therefrom into engagement with the rail of the upper sash, thereby forcing the same against the sash bead and locking both sashes against movement also preventing the sashes from rattling.

What is claimed is:—

A sash lock comprising a pair of separated attaching plates, each having a semi-circular threaded channel, a screw mounted in said channel and having a headed end, a pressure plate, a channeled lug on the pressure plate adapted to be removably engaged by the headed end of the screw to be moved in either direction thereby, means for holding the plates together in operative position and for securing the same to the sash, said plates having mating semi-circular channels on opposite sides of the threaded channel, and separated pins arranged on the pressure plate on opposite sides of the lug and adapted to engage said last named channels to guide the pressure plate and prevent the same from turning.

In testimony whereof I affix my signature in presence of two witnesses.

ASMUS D. GARDEMAYER.

Witnesses:

FRANCIS DUNN,
OLIVER DIBBLE.
